UNITED STATES PATENT OFFICE.

WALTER A. GOBLE, OF GRAND RAPIDS, MICHIGAN.

REGULATING-HOOK FOR PIANO-ACTIONS.

1,351,512.

Specification of Letters Patent. Patented Aug. 31, 1920.

Application filed November 10, 1919. Serial No. 336,995.

To all whom it may concern:

Be it known that I, WALTER A. GOBLE, a citizen of the United States of America, residing at Grand Rapids, in the county of 5 Kent and State of Michigan, have invented certain new and useful Improvements in Regulating-Hooks for Piano-Actions; and I do hereby declare the following to be a full, clear, and exact description of the invention, 10 such as will enable others skilled in the art to which it appertains to make and use the same.

This invention relates to a piano action, being concerned with a regulating device 15 therefore, specifically a regulating hook which may be very cheaply and economically manufactured, attached to and combined with the piano action in a very simple manner and one which may, by simply 20 bending the hook to different positions, regulate the action of the piano as desired.

For understanding of the construction by which these ends are attained reference may be had to the following description taken in 25 connection with the accompanying drawing, in which: Figure 1 is a side elevation of the operating parts of the piano action as is used to operate one of the hammers, the rail on which all of the said actions in a piano 30 are mounted being shown in transverse section.

Fig. 2 is a similar view with some parts not concerned with my invention removed, but showing the operation of the action at 35 the termination of the working.

Fig. 3 is a horizontal section taken on the line 3—3 of Fig. 1; and

Fig. 4 is a fragmentary front elevation of the action rail, jack and regulating hook 40 such as used with one hammer.

Like reference characters refer to like parts in the different views of the drawing.

I have shown the construction as it appears with one hammer in a piano. Inasmuch as all of the others are duplicates, a showing on one suffices for all. The piano action rail 1 extends the full length of the piano and a distance above and back of the key-board. From the upper portion there- 45 of a short flange 2 extends on which the hammer butt 3 is pivotally mounted; the hammer consisting of the upwardly extending rod 4 and the usual head (not shown in the drawing), is attached to and projects upwardly from the hammer butt. The under side of the hammer butt is covered

with felt, leather or similar material as indicated at 5. On the action rail 1 all of the various hammers of a piano are mounted in this manner, lying alongside of each other.

From the lower part of the rail 1 a wippen 6 extends downwardly to which a lever 7 is pivotally mounted extending forwardly from the wippen. A link 8 extends downwardly from the lever 7 and has the usual operative connection with a piano key whereby on depression of the key the lever 7 is thrown upwardly about its pivotal connection to the wippen 6. In front of the rail 1 a supporting post 9 is connected to and extends upwardly from the lever 7. A jack in the form of a bell-crank lever is pivotally mounted on the post 9 having an upwardly extending arm 10 which, normally, 75 at its upper end engages against the felt or leather 5 and a forwardly extending shorter arm 11 between which and the lever 7 a coiled compression spring 12 is located, the effect of which is to turn the upper end of the arm 10 to the rear. On the upper side of the forwardly extending shorter arm 11 a pad 13 of felt or like material is secured.

The regulating hook is preferably formed 85 of wire and consists of a section 14 threaded at one end so as to be readily screwed into the rail 1 and, at its opposite end, being turned at right angles to form a section 15. This hook is attached to the rail 90 1 in such position that the section 14 is located at one side of the arm 10 of the jack, while the section 15 turns across and normally lies a short distance above the pad 13 of its associated jack. 95

In operation when a piano key is depressed and the forward end of the lever 7 elevated, the first effect is to elevate the jack with the lever and thus turn the hammer about its pivot where connected to the flange 2, turning the hammer to the rear so that it will strike its associated wire. Immediately before the hammer strikes the wire the pad 13 comes into engagement with the section 15 of the regulating hook so that on continued 100 upwardly movement of the lever 7 the jack is turned about its pivot with a compression of the spring 12 and a movement of the upwardly extending arm 10 of the jack to the position shown in Fig. 2. The hammer under the influence of the momentum imparted to it will continue to move until it strikes the 105 110

piano wire and will then immediately return being free to do so by reason of the fact that the arm 10 of the jack has disengaged from the hammer butt and is out of the way.

5. Each of the piano jacks may be equipped with one of the regulating hooks including the two sections 14 and 15. These hooks are very easily manufactured and can be attached to the piano rail 1 very quickly and readily. While I have shown the ends of the regulating hooks threaded, it is of course apparent that any other method may be used such as pointing the end of the section 14 and driving the same into the rail 1. 15 For regulating the piano action it is only necessary to bend the section 14 either up or down as desired. This is a very simple operation. With this invention the regulation of piano actions is very much simplified. 20 The cost of manufacture in a piano having a large number of these actions to regulate is materially reduced. The construction is very durable and is not in any way liable to get out of order. Every hook is independent 25 of the others and may be independently bent either up or down for the regulation of the action with which it is associated. While I have shown the hook as made of wire having a circular cross section, it is of course, apparent that this construction may be widely varied in detail and the cross sectional shape as may be desired. The invention is defined in the appended claims and I consider myself entitled to all modifications of structure falling within their scope. 30

I claim:

1. In a piano action, a supporting rail, a piano jack pivotally mounted adjacent the supporting rail and having an arm extending upwardly adapted to engage a hammer butt, and a regulating hook secured to and extending from the rail and turned to pass in front of the upwardly extending portion of the jack, said hook being normally rigid but bendable to different positions, and said jack having a part extending away from its pivot and normally lying under the free end of the hook, substantially as and for the purposes described. 40
2. In combination in a piano action, a sup- 45

porting rail, a hammer pivotally mounted on said rail, a jack pivotally mounted in front of the rail and normally adapted to engage at its upper end with the hammer butt, and an individual regulating means attached 55 to and extending in front of the rail and having a part located in the path of movement of the jack to engage with the jack and disassociate it from the hammer butt at a predetermined point, said regulating means 60 being bendable to different positions to determine said point of disassociation, substantially as described.

3. In combination in a piano action, a horizontal action rail, a hammer pivotally mounted at its lower end at the upper part of the rail, a wippen pivotally mounted at its front end at the lower portion of the rail, a piano jack comprising an upwardly extending arm and forwardly extending portion of shorter length pivotally carried by the wippen in front of the rail, the upper end of the upwardly extending arm of the jack normally engaging with the hammer butt, and a wire hook attached to the rail 70 and extending in front thereof with its free end turned to normally lie above the forwardly extending portion of the jack, said wire being bendable to different positions, substantially as and for the purposes de- 80

4. In a construction of the character described, a supporting rail adapted to support pivotally mounted piano hammers, a jack adapted to operate each hammer mounted in front of the rail, and a regulating hook attached to the rail for each jack between the upper and lower ends of the jack and extending from said rail, said hook having a portion at its free end turned to lie in 90 the path of movement of the jack, said hook being normally rigid but bendable to different positions so as to engage with the jack at different times in the operation of the piano action to thereby regulate said 95 action, substantially as and for the purposes described.

In testimony whereof I affix my signature.

WALTER A. GOBLE.
